COMBINED DEPTH AND PRESSURE GAUGE FOR SCUBA DIVERS

Carlton L. Koehler, Box 236, Avalon, Calif. 90704

Filed July 19, 1972, Ser. No. 273,200

Term of patent 14 years

Int. Cl. D10—04

U.S. Cl. D10—85

FIG.1

FIG.2

FIG.3

FIG.4

FIG.5

FIG.6

FIG.7

FIG. 1 is a bottom front and right side perspective view of a scuba diver's depth and pressure gauge holder showing my new design;

FIG. 2 is a front elevational view of FIG. 1;

FIG. 3 is a rear elevational view of FIG. 2;

FIG. 4 is a right side elevational view of FIG. 2;

FIG. 5 is a left side elevational view of FIG. 2;

FIG. 6 is a top plan view of FIG. 2; and

FIG. 7 is a bottom plan view of FIG. 3.

I claim:

The ornamental design for a combined depth and pressure gauge for scuba divers, substantially as shown.
